(57) **CLAIM**

The ornamental design for a bird feeder as shown and described.

DESCRIPTION

FIG. 1 is a front perspective view of a bird feeder, showing my new design;

FIG. 2 is a front elevational view thereof;

FIG. 3 is a rear elevational view thereof;

FIG. 4 is a left elevational view thereof;

FIG. 5 is a right side view thereof;

FIG. 6 is a top plan view thereof;

FIG. 7 is a partial enlarged view of FIG. 1;

FIG. 8 is a partial enlarged view of FIG. 1; and,

FIG. 9 is a partial enlarged view of FIG. 2.

The broken lines in the figures are for the purposes of illustrating portions of the bird feeder, which form no part of the claimed design.
